UNITED STATES PATENT OFFICE.

HARRY C. STUTZ, OF INDIANAPOLIS, INDIANA.

DESIGN FOR AN AUTOMOBILE-HEADLIGHT.

53,619.

Specification for Design.

Patented July 15, 1919.

Application filed April 7, 1919. Serial No. 288,391. Term of patent 14 years.

To all whom it may concern:

Be it known that I, HARRY C. STUTZ, a citizen of the United States, residing at Indianapolis, in the county of Marion and State of Indiana, have invented a new, original, and ornamental Design for an Automobile-Headlight, of which the following is a specification, reference being had to accompanying drawing, forming a part thereof.

Figure 1 is a front elevation; Fig. 2 a side elevation; Fig. 3 a rear elevation; and

Fig. 4 a perspective view, on a smaller scale, of an automobile head-light showing my new design.

I claim:

The ornamental design for an automobile headlight, as shown.

In witness whereof, I have hereunto set my hand at Indianapolis, Indiana, this fourth day of April, A. D. one thousand nine hundred and nineteen.

HARRY C. STUTZ.
